UNITED STATES PATENT OFFICE.

BRUCE BORLAND, OF CHICAGO, ILLINOIS.

CAR SEAL.

Application filed December 13, 1920. Serial No. 430,263.

To all whom it may concern:

Be it known that I, BRUCE BORLAND, a citizen of the United States, residing at Chicago, in the county of Cook and State of Illinois, have invented certain new and useful Improvements in Car Seals, of which the following is a specification.

This invention relates to seals such as are commonly used for sealing cars, receptacles, 10 or other articles or devices, where it is desired to prevent their being opened except by authorized persons.

The objects of this invention are to provide a seal of improved form or character; 15 to provide a seal which may be readily and cheaply constructed; to provide a seal having secured locking mechanism and constructed so that if the locking mechanism is tampered with, the seal will be apt to be 20 broken; and to provide such other advantages and improvements as will appear more fully from the following specification.

I have shown a preferred form of my invention in the accompanying drawings in 25 which;

Fig. 1 is a perspective view.

Fig. 2 is a plan view of the locking portion.

Fig. 3 is a longitudinal, sectional view of 30 the locking portion and,

Fig. 4 is a bottom plan view.

It will be understood that these seals are usually made of tin or light sheet metal and the figures shown in the drawings are on enlarged scales.

As shown in these drawings, the seal comprises a strip 5, which forms the loop to be passed through the lock or other devices to which the seal is applied. One end of the 40 loop 5 is somewhat enlarged to form a locking end or head 6. The central portion of this head is elevated or stamped up to form a seat 7 for the coacting locking member. A cap 8 fits upon the head 6 and is held in 45 engagement therewith by means of the flange 9 on the head 6, which is bent over the adjacent edge or flange 10 of the cap. It will be noted that the head 6 is in alignment with the adjacent portion of the strip 5, but 50 is bent downwardly so that there is a shoulder 11 between these portions. In other words the head and flange forms a cup-like extension at the end of the loop and one of the principal features of this invention is 55 the arrangement whereby a part of the flange 9 as shown at 12 is continued up

along the sides of this shoulder so as to strengthen the locking member.

The cap 8 has an inwardly projecting tongue 13 which lies adjacent to the seat 7 and is somewhat yielding to permit the insertion of the locking member. This tongue is of channel shape or has side flanges 14 which engage with the top of the cap for a short distance beyond the bend as shown 65 at 15.

The opposite end of the strip 5 is provided with a locking tongue 16, which is adapted to be inserted between the seat 7 and the tongue 13. The tongue 16 is bent downwardly or offset to form a shoulder 17, which is adapted to rest against the adjacent shoulder 18 of the tongue 13. The locking tongue 16 also has a projection 19 for engagement with the end of the tongue 75 13 and has side flanges 20, which fit over the flanges 14 of the tongue 13.

When the seal is to be locked, as shown in Figures 1 and 3 the locking tongue 16 is inserted between the tongue 13 and the seat 80 7 and pressed inwardly until the end of the tongue 13 engages with the projection 19, to lock the same in position. At this time the shoulder 17 is substantially in contact with or rests against the shoulder 18. 85 When the parts are thus assembled it is difficult or practically impossible to unlock the same or tamper with the latching mechanism without breaking the seal or otherwise showing that the device has been tampered 90 with.

The flanges or nesting arrangement of the locking tongue and spring tongue prevents the insertion of any tool or device for raising the spring tongue. Furthermore the cup-shape or flanged form of the 95 head 6 greatly stiffens the same and prevents the parts from being readily fastened together if the fastening head or catch is broken off from the strip. It will also be noted that the outer walls of the upwardly 100 extending seat 7 make an abutment around the inner portion of the cup or head 6 so that the sides of the cap 8 cannot be readily pressed inwardly or collapsed so as to withdraw the flange 10 from the coacting flange 105 9 of the cup. Furthermore by having the continuous flange around the cup 6 there are no ends presented whereby a tool might be inserted for bending up or loosening the flange after it has been crimped into 110 position. The hole 21 is preferably placed in the strip 5 adjacent to the catch or tongue

13 so that the strip is apt to be broken at this point if this portion of the seal is tampered with. The hole also furnishes a convenient means for carrying the device.
5 Having thus described my invention, what I claim and desire to secure by Letters Patent is:

- 10 1. A seal comprising a strip having a substantially cup shaped locking head at one end with a continuous flange around the entire periphery thereof and having an upwardly raised seat in the bottom, a cap formed of a separate piece and fitting over said head, a portion only of said flange being bent down to engage with the edge of the cap to hold it securely in position, an inwardly projecting tongue on said cap and a locking tongue on the opposite end of the strip for engagement with said seat and tongue.
- 15 2. A car seal comprising a strip having a depressed flanged locking head at one end thereof with its flange extending around the entire periphery thereof, said head having an upwardly projecting seat, a cap secured to said head to form a pocket, said cap hav-

ing an inwardly projecting flanged tongue, the opposite end of the strip having a flanged locking tongue adapted to be inserted between the seat and said tongue and to rest on said seat.

3. A car seal comprising a strip having an offset flanged head at one end thereof, with an upwardly raised seat, the cap secured to said head to form a pocket, said cap having an inwardly projecting flanged and shouldered tongue the opposite end of the strip having a flanged shoulder locking tongue with a projection for engagement with the end of the first named tongue, the arrangement being such that the locking tongue rests on the seat and nest over the first named tongue when in locking position.

4. In the car seal, the combination of the strip having a pocket at one end with a raised seat in the bottom thereof, a flanged and shouldered tongue in said pocket and a flanged and shouldered locking tongue at the opposite end of the strip for engagement with the seat and the first named tongue substantially as described.

BRUCE BORLAND
